RAILWAY CAR TRUCK

Rudolph Leppla, Pittsburgh, Pa., assignor to
McConway & Torley Corporation, Pittsburgh,
Pa., a corporation of Pennsylvania

Application December 31, 1942, Serial No. 470,788

6 Claims. (Cl. 105—208.1)

This invention relates to railway car trucks of the type in which the bolster is yieldably supported from a vertically movable cross member such as a transom which is slidably mounted at its ends in the truck side frames.

In trucks of the transom type the transom serves to hold the side frames in position and is ordinarily made in the form of a one-piece casting, consisting of a pair of spaced cross beams and end portions of rectangular form which are adapted to slidably fit in the side frame openings and which project downwardly below the bottom of the beams for a considerable distance to provide guide members of sufficient height to hold the frames against tilting movements with respect to the transom. In making such a casting it is difficult to prevent some distortion of the ends in cooling, which may cause one end portion or the other of the transom to be disposed at an angle slightly less or slightly greater than 90° to the cross beams. Such distortion of a transom casting makes necessary a straightening operation, which is difficult and expensive.

The present invention has for an object to provide a transom construction which eliminates the above-mentioned difficulty, insures proper assembly of the side frames and transom, and consequently reduces the cost of producing the transom and provides a better fit between the transom guide members and the side frames.

A further object of the invention is to provide an adjustable seat between the transom and the spring plank supporting links, whereby the inclination of the links may be adjusted.

A further object is to provide bearing blocks for the pivots of the spring plank supporting links which are detachably mounted in the transom so that they may be readily replaced when worn or otherwise damaged.

A further object of the invention is to provide a mounting of the transom in the truck side frames which includes a pad for cushioning the impact of the transom upon the side frame, said mounting being designed to permit compression of the transom supporting springs to near the limit of compression of the springs and prevent the imposition of excessive loads that would cause the springs to go solid if the cushioning pad should be omitted or be lost while the truck is in service, whereby a pad of substantial thickness may be employed without danger of injury to the springs.

With the above and other objects in view, the invention may be said to comprise a car truck

as illustrated in the accompanying drawings, hereinafter described and particularly set forth in the appended claims, together with such variations and modifications thereof as will be apparent to one skilled in the art to which the invention pertains.

Reference should be had to the accompanying drawings, forming a part of this specification, in which:

- 10 Fig. 1 is a fragmentary side elevation of a truck embodying the invention, portions of the side frame, the transom, and a supporting spring being broken away and shown in section;
- 15 Fig. 2 is a side elevation of the transom-positioning guide member and spring cap;
- 20 Fig. 3 is a top plan view of the guide member shown in Fig. 2;
- 25 Fig. 4 is a fragmentary top plan view of the truck, with a portion of the side frame broken away and shown in section;
- 30 Fig. 5 is a vertical transverse section, taken on the line indicated at 5—5 in Fig. 1;
- 35 Fig. 6 is a section taken on the line indicated at 6—6 in Fig. 5;
- 40 Fig. 7 is a fragmentary side elevation of one end of the transom and spring plank;
- 45 Fig. 8 is a section on the line indicated at 8—8 in Fig. 5;
- 50 Fig. 9 is a section taken on the line indicated at 9—9 in Fig. 5;
- 55 Fig. 10 is a section taken on the line indicated at 10—10 in Fig. 5;
- Fig. 11 is a fragmentary side elevation, partially broken away and shown in section, of a modified truck construction embodying the invention; and
- Fig. 12 is a transverse vertical section taken on the line indicated at 12—12 in Fig. 11.
- In the accompanying drawings, one side portion only of the truck is illustrated, it being understood that the opposite side of the truck is identical with the side shown in the drawings.
- The truck shown in Figs. 1 to 10 has side frames A, and transom B, a bolster C, and a spring plank D, the transom B being a cross frame member connecting the side frames A, and the bolster C being yieldably supported on the spring plank D, which is flexibly suspended from the transom. The truck side frames A are of a conventional freight car type, having top and bottom chords 1 and 2, and journal boxes 3 at opposite ends of the frame to which the ends of the chords 1 and 2 are connected. In trucks of the type to which the present invention relates the weight of the car body supported on the

truck is imposed upon the bolster, transmitted through suitable cushioning means from the bolster to the transom, and through a second cushioning means from the transom to the side frames, which impose the weight upon the axles received in the journal boxes 3. Vertical guide columns 4 connect the top and bottom chords 1 and 2 and these columns are spaced apart to provide a central opening 5 in the side frame. Each of the columns 4 has an inwardly offset guide portion 6, which may be provided with a wear plate 7 on its inner face for engagement with the end portion of the transom A.

Across the bottom of the opening 5 the bottom chord 2 is in the form of an upwardly facing channel, which is provided with laterally extending side flanges 8 along its upper edge. Centrally of the opening 5 the lower chord 2 has an integral web 9 intermediate the top and bottom of the channel, the web 9 providing a seat for limiting downward movement of the transom. A suitable pad 10 may be mounted on the web 9 to cushion the impact of the transom.

The transom B comprises a pair of spaced parallel cross beams 11 and integral end portions 12 which connect the cross beams 11. The cross beams 11 may have inwardly offset portions 13 at the ends which extend into the openings 5 of the side frames, and to which the connecting members 12 are integrally joined. The end members 12 have depending arms 14 at opposite ends thereof which are disposed at right angles to the cross beams 11. The cross beams 11, connecting members 12 and arms 14, are preferably tubular and of rectangular cross section joined together in a one-piece casting, the tubular arms 14 being open at their lower ends.

Adjacent the top thereof the end portion 12 of the transom is provided with laterally projecting guide lugs 15 and 16 which are adapted to straddle the projecting portions 6 of the guide columns. The lower portion of the transom end is guided in the side frame by a guiding and positioning member 17, which is secured in adjusted position to the lower ends of the arms 14. The positioning member 17 has a depressed central portion 18, which projects into the channel of the bottom chord, and which cooperates with the lugs 15 and 16 to maintain the side frames in planes at right angles to the planes of the cross beams 11.

The depressed portion 18 is preferably of a size to enter the channel of the bottom chord and is engageable with the pad 10 on the cross web 9. Opposite ends of the member 17 are formed to provide flat spring seats 19 on the under sides thereof directly beneath the depending arms 14. The positioning member 17 has upwardly extending end flanges 20 which engage the outer sides of the arms 14, and it is also provided with intermediate flanges 21 which engage the inner sides of the arms 14. The member 17 is also provided with horizontal side flanges 22 which overlie the side flanges 8 of the bottom chord. The guide member 17 is secured to the lower ends of the arms 14 with the depressed portion 18 thereof properly centered with respect to the guide lugs 15 and 16 by any suitable means such as by welding.

Coil springs 23 are interposed between the seats 19 and the bottom wall of the bottom chord 2, the springs 23 being disposed directly beneath the depending arms 14 of the transom. By providing a positioning member 17, which is rigidly secured in adjusted position to the lower

ends of the arms 14, the necessity for truing distorted transom castings is eliminated. If the transom casting is somewhat distorted, the positioning member 17 may be positioned inwardly or outwardly with respect to the centers of the arms 14, so as to bring the guide portion 18 into a position in which it is properly centered with respect to the upper guide members 15 and 16. The member 17 may then be welded or otherwise secured to the arms 14, so that a proper fit is obtained between the transom and side frames regardless of any distortion in the ends of the transom. The portion 18 of the bottom guide members 15 and 16 so that lateral tilting of the side frames with respect to the transom is prevented.

The end flanges 20 also enter into the side frame channel where the walls and flanges 8 curve upwardly to connect with columns 4.

Thus the combination of the upper guide members 15 and 16, portion 18 of the positioning member 17 as well as the flanges 20 of the same all serve to restrain the lateral movement between transom and side frames tending to keep the truck square laterally within close limits.

The cross web 9 of the bottom chord is so positioned with respect to the side flanges 8 of the chord that when the pad 10 is in place on the web 9 the flanges 22 of the positioning member will be slightly above the flanges 8 when the depressed portion 18 is resting on the pad 10. The clearance between the flanges 8 and 22 is, however, less than the thickness of the pad 10, so that if the pad 10 should be omitted or become lost the positioning member will seat upon the flanges 22 instead of upon the web 9, the flanges 22 serving as auxiliary or safety stops to prevent the bottom springs going over solid. It is desirable to provide for compression of the springs 23 to very near their limit of compression. It is not, however, desirable to permit excessive loads to be imposed upon these springs, which would cause these springs to go solid. By limiting the downward movement of the transom as above explained, the springs 23 may be subjected to very nearly their capacity load but are effectually protected against damage by the imposition of excessive loads.

Midway between their ends the parallel cross beams 11 are provided on their inner upper edges with arcuate recesses 24, which are adapted to receive a center bearing 25, which may be formed integrally on the bolster C. The recesses 24 are so proportioned that the center bearing 25 is permitted to have a limited amount of vertical play and also a limited amount of endwise movement in the recesses so that the bolster C may have corresponding movements. The bolster C is supported at its ends upon suitable springs, such as coil springs 26, which are shown mounted between top and bottom seating plates 27 and 28 on the under side of the bolster and on the spring plank D.

The recessing of the cross beams permits the use of straight cross beams and also serves the dual purpose of providing an additional lateral limiting stop for the bolster as well as a vertical limiting stop to prevent the bolster springs from going solid.

The springs 23 are preferably relatively soft springs of a capacity suitable for cushioning lightly loaded cars. The springs 26 are of a capacity to cushion the maximum load which the car is designed to carry. With a lightly loaded car the

normal vibrations are within the cushioning range of the springs 23 but whenever the amplitude of oscillation becomes excessive the transom engages the bottom chord, the springs 23 are stopped off and further movement is cushioned by the stiffer springs 26 which then function as snubbers to reduce the bounce. When the car is heavily loaded the springs 23 have only a very slight deflection before they are stopped off and the major part of the cushioning action is performed by the springs 26. The springs 23 are, however, at all times effective to maintain a proper distribution of weight to the wheels.

The spring plank D has a saddle member 29 attached to the under side thereof at each end, and each saddle member has laterally spaced, rectangular eye or loop members 30, which are adapted to receive a pivot bar 31. Each pivot bar 31 has a rounded top edge 32, which engages in concave bearings 33 on the under side of the saddle 29. The pivot bars 31 extend across the under side of the spring plank, and the opposite ends thereof are seated in slots 34 formed in the lower ends of suspension links 35, the bars 31 having notches 36 on the under side thereof which are of a width to receive the links 35 at the lower ends of the slots 34, so that the bar 31 is restrained against endwise movements with respect to the suspension links.

The links 35 disposed on opposite sides of the spring plank D extend upwardly through slots 37 formed in the cross beams 11 and carry trunnions or pivot members 38 at their upper ends which rest in sockets 39 formed in bearing blocks 40, which are seated in recesses 41 formed in the tops of the cross beams 11. Each bearing block 40 has a central slot 42 through which the link 35 extends. The recesses 41 are preferably substantially rectangular in form, and the blocks 40 are shaped to fit in the recesses. Central portions of the recesses 41 preferably extend the full width of the upper faces of the cross beams 11, but adjacent the ends of the recesses 41 flanges 43 are provided on opposite sides thereof which engage in recesses on the underside of the blocks 40 and hold the blocks against lateral movements.

The pivot-receiving recess 39 of each of the blocks extends across the full width of the block and is disposed nearer one end of the block than the other. Each of the blocks is reversible in its recess, so as to adjust the positions of the recesses 39 toward or away from the transom end and to thereby vary the inclination of the supporting links 35.

In Fig. 7 the blocks 40 are shown in a position reverse to that shown in Fig. 5, so that the links 35 are disposed at an inclination. The blocks 40 are readily detachable and replaceable, and blocks may be provided with the recesses 39 at various distances from the longitudinal center of the block, so that the desired adjustment of the links may be provided, either by reversing the blocks or by substituting bearing blocks. The provision of replaceable bearing blocks is advantageous for the additional reason that they may be replaced with new blocks when worn or damaged.

A safety bracket 44, in the form of a U-shaped strap secured at its ends to downwardly projecting integral flanges 45, formed in the cross beams 11, may be provided adjacent the spring carrying portion at each end of the spring plank D, so that in case of breakage of one of the pivot bars 31 or one of the links 35 the spring plank will be caught on the bracket 44 and be prevented from falling to the track.

In Figs. 11 and 12 of the drawings a modified form of the invention is shown, in which the side frames are provided with vertical guide columns 46, each of which has a pair of upper, inwardly projecting guide flanges 47 which receive projections 48, formed on the upper portions of the arms 49 of the transom ends. The bottom chords of the side frames have cross webs 50 beneath the columns 46 which serve to strengthen the frame at the juncture of the chords with the columns. The transom is provided with a positioning member 51, secured in adjusted position to the lower ends of the transom arms 49, the positioning member having a depressed central portion 52, which is received within the channel of the bottom chord, and spring seating portions 53 above the depressed portion 52 and beneath the lower ends of the arms 49. Springs 54 are interposed between the seating portions 53 of the positioning member and the bottom web 55 of the bottom chord, the web 55 being provided with lugs 56 for positioning the springs 54.

The positioning member 51 is provided with upwardly projecting flanges 57, which engage the sides of the arms 49, and which may be welded to the arms 49. The member 51 is also provided with depending end flanges 58 which serve to position the springs 54. Columns 46 are provided at their lower ends with inwardly projecting guide flanges 59, which are arranged in pairs and are spaced to receive the ends of the positioning member 51.

The bottom chord is provided with a cross web 60, adapted to support a cushioning pad, and the positioning member 51 is provided with side flanges 61, which overlie side flanges 62 of the bottom chord. The flanges 61 and 62 and web 60 are arranged in the same way as the corresponding elements in the modification first described.

The transom cross beams are provided with recesses 63 which receive reversible bearing blocks 64, provided with off-center sockets 65, to receive trunnions 66 of suspension links 67. Each pair of suspension links 67 carries a pivot bar 68, which engages with a saddle member 69 on an end of the spring plank 70. The linkage for suspending the spring plank from the transom is substantially the same as the linkage shown in connection with the modification first described.

The bolster and spring plank are provided with spring seating members 71 and 72 which receive the top and bottom bands 73 and 74 of an elliptic spring 75, which is preferably disposed beneath the bolster and parallel therewith, the outer end of the spring projecting outwardly between depending end members of the transom 49 above the positioning member 51.

It will be apparent that the provision of a separately formed guide member adapted to be secured in adjusted position to the end portions of the main casting, greatly simplifies the transom casting and reduces the cost of manufacture. Furthermore, the elimination of the straightening operation on the casting which requires a straightening machine provided with elaborate and expensive dies, effects a considerable saving in the cost of manufacture.

The provision of auxiliary stops in connection with the cushioning pad not only permits the springs to be compressed to very near their limit without danger of the springs going solid, but permits the use of a relatively thick cushioning pad if desired, the springs being stopped off be-

fore they have gone solid either by the pads or by the auxiliary stops.

It is to be understood that variations and modifications of the specific devices herein shown and described for purposes of illustration, may be made without departing from the spirit of the invention.

What I claim is:

1. In a truck, the combination with the side frames having top and bottom chords, and spaced columns connecting the chords and providing openings in the frames, of a transom having end portions engaging said columns and guided for vertical movement between said columns, said end portions projecting downwardly from the body of the transom, and guiding and positioning members secured in adjusted positions to the lower ends of the projecting portions, said positioning members having sliding engagement with the side frames.

2. In a truck, the combination with the side frames having top and bottom chords, and spaced columns connecting the chords and providing openings in the frames, of a transom comprising spaced cross beams, cross members connecting the ends of said beams, and arms depending from the ends of said cross members, said cross members and arms being adapted to fit between said columns, and a guiding and positioning member bridging the space between the lower ends of the arms at each end of the transom, each positioning member being secured in adjusted position to said arms, and being engageable with the side frame in which it is mounted, to position the side frame with respect to the transom.

3. A car truck having a side frame provided with top and bottom chords, and spaced guide columns connecting said chords and providing a central opening, the portion of the bottom chord beneath said opening being in the form of an upwardly opening channel, a transom having an end portion slidably mounted in said opening, said end portion having a positioning member at the bottom thereof which has spring seats at its ends, and a depressed portion between said seats adapted to enter the channel of the bottom chord, supporting springs mounted in said channel and engaging said seats, and stop members carried by said positioning member and bottom chord, to limit the downward movement of the transom.

4. A car truck having a side frame provided with top and bottom chords, and spaced guide columns connecting said chords and providing a central opening, the portion of the bottom chord beneath said opening being in the form of an upwardly opening channel, a transom having an end portion slidably mounted in said opening, said end portion having a positioning member at the bottom thereof which has spring seats at its ends, and a depressed portion between said seats adapted to enter the channel of the bottom chord, supporting springs mounted in said channel and engaging said seats, a cross web carried by the bottom chord beneath said depressed portion of the positioning member, a cushioning pad carried by said web, and side flanges on said positioning member overlying the flanges of the bottom chord, said side flanges being spaced above the bottom of the depressed portion a distance less than that between the top surface of the web and the top edges of the chord flanges, but greater than the distance between the top face of the pad and the top edges of the chord flanges.

5. A car truck having a side frame provided with top and bottom chords, and spaced guide columns connecting said chords, a transom comprising spaced parallel cross beams, an integral cross member connecting said beams at each end, and integral arms depending from opposite ends of the cross member, integral guide members carried by the transom ends adjacent the top thereof and straddling portions of said columns, and a guiding and positioning member secured in adjusted position to the lower ends of said arms, and engageable with the side frames, to hold the same against rocking movements with respect to the transom.

6. A car truck transom having a body portion in the form of a one piece casting that comprises a pair of spaced cross beams, an integral cross member connecting said beams at the ends thereof and parallel integral arms depending from opposite ends of each cross member, and a guiding and positioning member abutting the lower ends of the two depending arms at each end of said transom, each guiding member being secured to said arms in an adjusted position to compensate for distortion of the casting.
